UNITED STATES PATENT OFFICE.

MARK WRAY STAITHT, OF NEW YORK, N. Y.

IGNITION DEVICE.

1,163,479.

Specification of Letters Patent. Patented Dec. 7, 1915.

Application filed March 9, 1915. Serial No. 13,139.

To all whom it may concern:

Be it known that I, MARK W. STAITHT, a subject of the King of Great Britain, and who has declared his intention to become a 5 citizen of the United States, residing at New York city, in the county of New York and State of New York, have invented certain new and useful Improvements in Ignition Devices, of which the following is a 10 specification.

My invention relates to igniting means and particularly to a machine for igniting flash light powder charges, or cartridges, or sheets of flash light material, by means of a 15 fulminating body, such as a match, and the invention consists of the parts and the constructions, arrangements and combinations of parts which I will hereinafter describe and claim.

20 In the accompanying drawings forming part of this specification and in which similar reference characters indicate like parts in the several views; Figure 1 is an elevation of a match igniting machine embodying my invention. Fig. 2 is a longitudinal section of the same on the line A—B of Fig. 1. Fig. 3 shows the application of my machine to a support and to a flash sheet holder. Figs. 4 and 5 are details to be referred to.

25 A leading object of the present invention is to provide for the automatic ignition of a match or equivalent fulminate and the subsequent placing of the same in a position to ignite a flash material, as a flash sheet, 30 cartridge, or a charge of flash powder, such as is usually employed for photographic purposes.

In carrying out my invention I construct a machine with a suitable base, *a*, which may 40 be of any desired character. Preferably, the base is made of sheet metal, out of which is stamped suitable parts which serve as stops for limiting the movement of certain of the active agents of the machine, as I 45 will hereinafter describe.

The base is provided with a suitable bolt or stud, *d*, which is rigidly fixed to it and projects from the face thereof, upon which is pivotally mounted an appropriate holder, 50 *b*, said holder having its outer end provided with an aperture, *b*¹, for receiving the head end of a match, *b*². If desired, and to better frictionally hold the head of the match

in position in the aforesaid opening, the outer end of the holder may be split to form 55 more or less elastic or spring jaws which close upon the head of the match.

The holder has a thickened hub portion through which the bolt, *d*, projects, and the bore of said hub portion is enlarged and 60 made at an angle to the axis of the bolt or stud, as shown in Fig. 2, whereby the holder may, in addition to its axial movement about the stud, have a rocking movement in the 65 direction of the length of the stud and transverse to the face of the base, to facilitate the insertion of the match and the movement of the match head past the igniting surface hereinafter described, when setting the holder in its operative position. The 70 pivoted holder is also provided with a heel portion, *b*³, adapted to engage behind a suitable trigger, *e*, which is slidably mounted in bearings *e*', formed on or struck out from the base plate, said trigger being encircled by a coil spring, *f*, which allows the trigger to be depressed to release the holder, and which is adapted to expand and form an abutment for the heel end of the holder 75 whereby said holder is held against movement until released by the trigger, said trigger having, also, a finger piece, *g*, by which it may be depressed against the tension of its spring to release the holder, as will be 80 well understood in this art.

Surrounding the bolt or stud, *d*, is a spring, *c*, one end of which is fixed to the stud and the other end is fitted to an opening, *c*', formed in the holder, said spring adapted to be placed under tension when the 85 holder is reset or moved into its operative position, and operating to project or carry the attached match over a corrugated or roughened surface, *h*, suitably secured to the face of the base, *a*, to thereby ignite the 90 match, when the trigger *e*, is withdrawn from its engagement with the heel end of the holder.

In the base plate is also formed an opening, *k*, behind which will be placed the flash 100 sheet, cartridge or other charge to be fired, said holder adapted to register with the ignited match head, when the holder is released in the manner before described, and the protruding match head is ignited by being forcibly drawn over the corrugated or 105

roughened surface, *h*. To insure the proper register of the match head with the aforesaid opening, *k*, I construct the base plate, *a*, with a shelf, stop or lug, *l*, which serves as an abutment for limiting the movement of the holder when the latter is released by the trigger mechanism before described.

The corrugated or friction surface, *h*, may be of any suitable character and may be secured to the base in any suitable manner and its function is to insure the ignition of the match as the head of the same is forcibly carried over said surface.

To limit the setting movement of the holder I may also provide the base plate with a stop, *m*, against which the heel portion of the holder will contact, as shown in Fig. 1, thus positioning the heel for its engagement by the trigger. The base is also provided with a stop, *n*, to prevent the holder from flying backward from left to right should the action of inserting the match push the holder away from the base far enough to clear the stop, *l*, or in case the operator should pull the same clear of the said stop *l*, by accident. This latter stop is set at an acute angle to the base so as to direct the torsional effort supplied by the spring to the holder in such a manner as will force the latter against the base plate completely covering the opening and thus prevent any flame from flaring back through the base. The holder is beveled to coincide with the above angle.

The machine described may be operatively held in position by various means. In Fig. 2, I show the machine as being associated with a flash sheet holder, 10, which may be of any suitable type and provided with a flash sheet, 11, but it will be obvious that any other form of ignitable substance as a flash powder, cartridge &c. may be employed without departing from the spirit of my invention.

The machine may be supported by any suitable means. For instance in Fig. 2, I show the machine as supported from a table or shelf by a suitable clamp, 12, having a seat or socket for a rod, 13, which is fitted into a suitable opening formed in the base plate, which may be enlarged or thickened for the purpose or provided with a socket, *a*, as shown in Fig. 5, which socket may also serve as the means for the attachment of a handle, 14, if it is desired to hold the machine in the hand during the ignition of the charge.

If it is desired to operate the machine from some remote point a suitable cord, 16, or other flexible connection may be attached to the trigger and thence carried through an appropriate guide so that when a pull is exerted upon the cord the trigger is depressed against the tension of its spring, *f*, to release the heel end of the match holder

and allow the spring, *c*, to turn the holder about its axis and ignite the match by carrying the same forcibly over and into contact with the corrugated surface, *h*, before mentioned.

In operation, a match is inserted in the holder so that the head only of the match protrudes through the hole, *k*, in the base. The holder may now be pulled outwardly away from the face of the base by grasping the match and turning the holder, say, to the left until the heel, *b*, of said holder comes into engagement with the stop, *m*, as shown in Fig. 1, in which position the heel of the holder will be engaged by the trigger. To ignite the match the trigger is depressed, either by the finger engaging the head, *g*, or by pulling upon the spring or other flexible connection, when the spring, *c*, reacts to turn the holder about its axis and thereby carry the match head across in frictional engagement with the corrugated surface, *h*, thereby igniting the match head and carrying the flaming head into register with the opening, *k*, to permit the flame to pass through this opening and ignite the flash sheet or charge at the other side of the base, said holder being limited in this movement by the stop or abutment, *l*, as before described.

The device described is intended primarily to provide facilities for the safe, reliable and more extended use of flash light combustible used chiefly in photography. The method of ignition described eliminates the possibility of an accident by the premature ignition of the flash light combustible; it enables a photographer to obtain better results because of the fact that his undivided attention can be concentrated on his subject up to the instant of the ignition of the flash light material; it extends the field of outdoor flash light work by reason of the certainty of ignition in windy localities; it extends the field of all flash light work as the mechanism may be operated from a remote point and, consequently, the photographer may include himself in any picture desired; and it provides a simple arrangement for animal self photography or for detective work.

Having thus described my invention what I claim as new and desire to secure by Letters Patent is:—

1. An automatic match-igniter comprising a base provided with a flame aperture; a match-holder pivotally mounted on the base adapted to swing crosswise thereof and to carry an ignited match into register with said opening; a surface over which said holder carries the match in frictional engagement; a torsional spring connected to the holder adapted to be placed under tension when the match and its holder are moved out of register with said opening, said holder having a heel end; a spring-

pressed trigger adapted to engage the heel-end of the holder to retain said holder under tension in operative position; and means for tripping the trigger to allow the holder 5 to carry the match into register with said opening.

2. In an automatic match-igniter, the combination with a base having a fixed stud projecting from the face thereof, said base 10 having a flame opening; a holder having a hub-portion mounted upon the stud, said holder having a heel at one end and having an aperture at the opposite end adapted to carry a fulminate; a friction surface on the 15 holder adapted to be engaged by the fulminate to ignite the latter during a swinging movement of the holder; a spring surrounding said stud having one end fixed thereto and the opposite end engaging the holder whereby the spring is placed under tension 20 when the holder is moved into operative position, said spring re-acting to move the holder about the stud and carry the ignited fulminate into register with said flame opening; a spring-pressed trigger adapted to engage the heel of the holder to retain said 25 holder in its operative position; and means for operating the trigger.

3. In an automatic match-igniter, the combination with a base having a fixed stud projecting from the face thereof, said base 30 having a flame opening; a holder having a hub-portion mounted upon the stud, said holder having a heel at one end and having an aperture at the opposite end adapted to carry a fulminate; a friction surface on the 35 holder adapted to be engaged by the fulminate to ignite the latter during a swinging movement of the holder; a spring surrounding said stud having one end fixed thereto and the opposite end engaging the holder whereby the spring is placed under tension 40 when the holder is moved into operative position, said spring re-acting to move the holder about the stud and carry the ignited fulminate into register with said flame opening; a spring-pressed trigger adapted to engage the heel of the holder to retain said 45 holder in its operative position; and means for operating the trigger, said hub portion 50 of the holder having a bore inclined to the axis of the stud whereby said holder may

yield in a plane substantially at right angles to the face of the base.

4. In an automatic match-igniter, the combination with a base having a fixed stud projecting from the face thereof, said base having a flame opening; a holder having a hub-portion mounted upon the stud, said holder having a heel at one end and having an aperture at the opposite end adapted to carry a fulminate; a friction surface on the holder adapted to be engaged by the fulminate to ignite the latter during a swinging movement of the holder; a spring surrounding said stud having one end fixed thereto and the opposite end engaging the holder whereby the spring is placed under tension when the holder is moved into operative position, said spring re-acting to move the 60 holder about the stud and carry the ignited fulminate into register with said flame opening; a spring-pressed trigger adapted to engage the heel of the holder to retain said holder in its operative position, said base 65 having a socket, a support engaging said socket, and means for operating the trigger from a distant point.

5. An automatic match-igniter comprising a base having a flame aperture; a match-holder pivotally mounted on the base adapted to swing crosswise thereof and to carry an ignited match into register with said opening; a surface over which said match-holder carries the match in frictional engagement; a torsional spring connected to the holder adapted to be placed under tension when the match and its holder are moved out of register with said opening, said holder having a heel-end; a spring-pressed trigger adapted to engage the heel-end of the holder to retain said holder under tension in operative position; and means for tripping the trigger to allow the holder to carry the match into register with said opening, said match-holder being mounted to rock in a plane substantially at right-angles to the plane of its swinging movement.

In testimony whereof I affix my signature in presence of two witnesses.
